UNITED STATES PATENT OFFICE.

JAS. D. WILLOUGHBY, OF CARLISLE, PENNSYLVANIA.

CURRIER'S BEAM AND KNIFE.

Specification of Letters Patent No. 9,207, dated August 17, 1852.

To all whom it may concern:

Be it known that I, JAMES D. WILLOUGHBY, of Carlisle, in the county of Cumberland and State of Pennsylvania, have invented 5 new and useful Implements for Currying Leather; and I do hereby declare that the following is a full, clear, and exact description of the same, reference being had to the accompanying drawings, forming part of 10 this specification, in which—

Figure 1 is a perspective of the improved beam, the gages or knife guides thrown forward, the better to exhibit the improvement on the sides of the beam; Fig. 2, a modification 15 of the beam and gages; Fig. 3, a view of the improved knife, and Fig. 4, a modification of the same.

The nature of my improvement of the beam, consists in attaching or adapting 20 gages, or guides for the knife either stationary or movable to the currier's beam or to the foot thereof, and also in attaching spring flaps to the sides of the beam or to the gages, by which I am enabled to clamp 25 or secure the hide to the beam, instead of requiring the knee of the workman to retain the double hide to the same, and as the gages or guides may be set, leather of any desired and regular thickness may be 30 obtained without that skill and judgment necessarily required and exercised in the use of the ordinary beam, at the same time the operator is enabled to turn out more curried leather, there being no lost time in 35 folding and feeling for thickness. It is admirably adapted to dressing harness leather, which is required to be of uniform thickness, and in the finer varieties such as morocco kid, &c., the risk of cutting through 40 is reduced.

The improvement in the knife, which in its general appearance resembles the ordinary currier's knife is in the construction 45 of the handle, it being so arranged between the knife plates, that by a movement of the handle, the edge of the knife may be thrown nearer the face of the beam, without altering the gages or guides on the beam; this is done either by an eccentric or a slotted bar, 50 passing between the plates, constituting the stock of the knife.

To enable others skilled in the art to make and use my invention I will proceed to describe its construction and operation.

55 In Fig. 1, A represents the base or foot block of the currier's beam; B, the beam

firmly secured in A (or it may if desired that the gages should be stationary, be made adjustable). C C are hinged side flaps attached to the beam, (provided with 60 spring a' placed between their under sides, and edges of the beam, shown in dotted line, to throw them out in close contact with the sides of the gages,) and acts as clamps to the leather placed over the beam; instead 65 of hinged flaps and springs, thick portions of any elastic substance may be used as a substitute. D, D, are gages, or guides for the knife, made of suitable pieces of wood or metal and sufficiently strong to embrace 70 and retain the leather between their sides and the edges of the beam; they also strain the leather and remove wrinkles, and are equally adapted to the plain or common beam; the gages are united by cross pieces 75 d d' secured in mortises, the upper cross piece d merely sustains the gages, but the lower one d' serves also the purpose of an adjustment, by screws c c inserted in the end of the base or foot A. The edges of 80 the gages are made straight from the top to the recess or hollow E E in which the knife may be laid. They have motion on the pivot F placed in the secondary block G, secured to the base A (by screws passing 85 through slots in G,) and may be thrown forward, when changing the leather on the beam. By the secondary block G the gages may be moved, and assisted by the screws c c arresting the cross piece d' the parallelism 90 of the gages with the face of the beam regulated, and thus give the desired thickness to the leather. The knife is formed of two plates H provided with screws h h passing through them clamping and securing the 95 steel blades I, I, between them, through the center of the stock thus formed by the plates, passes the handle J, the portion j j intended to rest upon and slide on the gages D D of the beam, is made round, but the portion 100 K passing between the plates in dotted line is reduced in diameter, but is not concentric with j j, being eccentric, the object of which being, by turning the handle J the eccentric acts on the stock H and throws the edge of 105 the knife either from, or toward, the beam; there is a modification of the same in Fig. 4, and the same result obtained by a bar l passing through the handles m furnished with diagonal slots o o o therein, and operated on by a screw nut n constituting one of 110 the handles, by the turning of said nut n

the bar *l* is made to project beyond the thickness of the handle *m*, and by drawing the slot on the bolts *p p* thus shift the knife from or toward the beam.

5 My improved beam admits of the use of the ordinary knife, but the improved one has the advantage of not requiring the gages to be so frequently altered, and the gages, when a quantity of leather of one thickness 10 is desired, may have stops placed behind their back edges; the knife is also provided with a set screw by which the handles may be retained in position.

A modification of the improvement to the 15 beam is shown in Fig. 2. A represents the base or foot block; B, the ordinary beam secured in the cross piece of the base; D D, movable gages connected with the posts 3, 3, by pins or bolts passing through angularly 20 placed slots 4, 4 in D; by depressing D the gages are made to advance in front of the face line of the beam, if additional thickness is required in the leather.

In the use of the improved beam the wet 25 leather is thrown across the face of the beam B and over the flaps C, C, drawing it smooth and free of wrinkles; the guides or gages D, D, are then brought into the position shown in dotted line, and thus clamp 30 the leather between the inner side of D and outer side of C; the springs *a'* between the inside of C and the edge of the beam force the flaps C outward and thus clamp the

leather. If the improved knife is used, the edge of the blade is applied to the leather, 35 the handles sliding on the edges of the gages D, said gages having been set to the required thickness desired in the leather, and is thus carried with certainty and facility, free of risk of cutting through and to great regularity of thickness independent of any great skill of the workman, who only has to observe to turn the eccentric *j*, on the handle J, as the reduction of the leather requires.

What I claim as my invention and desire 45 to secure by Letters Patent is,

1. The construction of a currier's beam B with flaps C C on its edges, furnished with springs *a'* and gages D D or their equivalent, for the purpose of dispensing with the 50 kneeing and prevention of cutting through and production of regular thickness of leather.

2. I also claim the construction of a knife made adjustable by the eccentric handle J, 55 *j*, *k*, or its equivalent in connection with the gages or guides D D, substantially as and for the purpose set forth in the foregoing specification and accompanying drawings.

In testimony whereof I have signed my 60 name hereunto before two subscribing witnesses.

J. D. WILLOUGHBY.
